(57) **CLAIM**

The ornamental design for a landscaping block, as shown and described.

DESCRIPTION

This application is related to U.S. Ser. No. 29/533,763, filed Jul. 22, 2015, entitled “Landscaping Block” and to U.S. Ser. No. 29/533,764, filed Jul. 22, 2015, entitled “Landscaping Block”, the contents of both of which are hereby incorporated by reference herein.

FIG. 1 is a top plan view of a landscaping block;

FIG. 2 is a bottom plan view thereof;

FIG. 3 is a first side elevational view thereof;

FIG. 4 is a second side elevational view thereof;

FIG. 5 is a third side elevational view thereof; and,

FIG. 6 is a fourth side elevational view thereof.

The broken lines in the figures depict portions of the landscaping block that form no part of the claimed design.
